COIN AND SLUG SEPARATING DEVICE

Walter A. Tratsch and William Patzer,
Chicago, Ill.

Application June 18, 1936, Serial No. 85,877

5 Claims. (Cl. 194—101)

This invention relates to a coin and slug separating device.

It is an object of this invention to provide an improved coin and slug separating device which is relatively simple and inexpensive in construction and efficient in use.

Another object of the present invention is to provide a new and improved coin and slug separating device for preventing fraudulent coins, tokens, slugs, etc., from entering into or operating a coin-operated machine or apparatus with which the new coin and slug separating device is associated.

Another object of the present invention is to provide a new and improved device for preventing a magnetically attractive or steel slug from entering into or operating the machine or apparatus with which the new coin and slug separating device is associated.

An additional object of the invention is to provide a new and improved device for ejecting a magnetically attractive or steel slug out of the coin chute, which is embodied in and forms a part of the new coin and slug operating device, and into a discharge chute which is associated with the same.

A further object of the present invention is to provide a new and improved device for preventing a fraudulent and relatively light slug, such, for example, as a paper or cardboard disc, from operating a machine, apparatus or the like with which the new selecting device is associated.

Still another object of the present invention is to provide a novel device for ejecting a relatively light slug, such for example, as a paper or cardboard disc, or the like, out of the coin chute, which is embodied in the new device, and into a discharge outlet which is provided in the same.

Another object of the present invention is to provide a novel device for detecting and ejecting fraudulent coins, tokens or slugs of a material identical to the standard U. S. five-cent piece but of a slightly lesser diameter.

Another object of the present invention is to provide a novel device for detecting and ejecting fraudulent coins, tokens, slugs or the like, of a material known as "Linotype metal", which is comparatively immune to magnetism, yet is relatively softer with respect to the standard U. S. five-cent piece.

Another and important object of the present invention is to provide a novel device for effecting a selection between fraudulent slugs or tokens, such as brass, copper, lead, zinc, Linotype

metal and aluminum slugs or discs, and a coin having the intended and proper metallic composition, such as the standard U. S. nickel, dime, quarter or the like.

A further object of the present invention is to provide a novel device for effecting a separation between fraudulent slugs or tokens, such as brass, copper, aluminum, Linotype metal, lead and zinc slugs and the like, and a coin having the intended or proper composition and dimensions, such as a nickel, dime, quarter or the like, whereby the fraudulent slugs will be discharged or diverted from the coin chute of the device onto a discharge outlet provided therefor, in the device, and the coin having the proper and intended metallic composition will be discharged from the coin chute into another discharge outlet which is provided in the device for the reception of the same.

Other objects will appear hereinafter. 20

The invention consists in the novel combination and arrangement of parts to be hereinafter described and claimed.

The invention will be best understood by reference to the accompanying drawings showing the preferred form of construction, and in which:

Fig. 1 is an elevational view showing a preferred form of the new coin and slug separating device;

Fig. 2 is an enlarged view taken along line 2—2 in Fig. 1, showing the present invention associated with a cabinet;

Fig. 3 is an enlarged vertical sectional view taken on line 3—3 in Fig. 1;

Fig. 4 is an enlarged vertical sectional view of a part of the new device and is taken along line 4—4 in Fig. 1;

Fig. 5 is a bottom plan view partly in section and is taken along line 5—5 in Fig. 2;

Fig. 6 is a fragmentary vertical sectional view taken along line 6—6 in Fig. 1;

Fig. 7 is a vertical sectional detail view of the present invention as seen along line 7—7 in Fig. 2, showing the runway formed therein;

Fig. 8 is a fragmentary elevational view taken along line 8—8 in Fig. 3;

Fig. 9 is a sectional plan view taken along line 9—9 in Fig. 1; and

Fig. 10 is a vertical sectional view taken along line 10—10 in Fig. 7. 50

A preferred embodiment of the new coin and token selecting device is shown in the drawings, is therein generally indicated at 10, and comprises a body 11 in which is formed a tortuous coin chute, which is generally indicated at 55

12. Formed in the body 11 are two inlets 13 and 14 to the coin chute 12, the inlet 13 opening upwardly or vertically and the inlet 14 opening laterally or horizontally so that coins or tokens 5 may be inserted into the coin chute 12 either from above or from the side of the same.

The coin chute 12 includes an inclined upper portion 15 (Fig. 7) and formed in one wall 16 of this portion 15 of the coin chute 12 is a slot 10 or opening 17. The runway 15 has a bottom wall 18 which is beveled to urge coin tokens, slugs etc. in a direction away from the wall 16. Likewise formed on the wall 16 is a laterally extending rib or deflector 67 the long axis of which runs 15 in a plane substantially parallel to the runway 15; the forward end of this deflector 67 (left end Figs. 7 and 9) merges with the surface of the wall 16 and the deflecting surface 68 thereof 20 graduates toward the extreme projection at the opposite end (right end Figs. 7 and 9).

Pivotedly mounted, as at 18, (Fig. 3) upon the body 11 of the new selecting device is a magnet carrier 19 and mounted on and carried by this member 19 is a magnet 20, one edge 21 of this 25 magnet 20 being adapted to be projected into the slot or opening 17 which is formed in the wall 16 of the upper portion 15 of the coin chute 12, for a purpose to be described presently.

The pivoted magnet carrier 19 has an offset 30 arm 22 (Figs. 3 and 8) and projecting into an opening formed in the arm 22 of the magnet carrier 19 is a pin 23 which is carried by an operating lever 24. This operating lever 24 is pivotally mounted at one end thereof, as at 25, upon 35 the body 11 of the device.

Pivotedly mounted on the body 11 of the new device, as at 31, (Fig. 2), is an operating lever 32 and this operating lever 32 carries a pin 33. This pin or extension 33 of the lever 32 projects between a member 34 and an offset arm 35 of the latter (Fig. 3) and the member 34 forms one movable wall of the upper portion 15 of the coin chute 12 and is pivotally mounted upon the body 11 of the device, as at 18 (Figs. 1 and 3); 40 and engageable with the lower end portion of an arm 26 of the operating lever 32 is the inner end portion 27 of an actuating member or plunger 28 which is slidably mounted in a support 29 which forms one wall of the cabinet of the coin-controlled machine or apparatus with which the new device is associated, this actuating member or plunger 28 being normally urged into its initial position (as in full lines, Fig. 2) by means 45 of a resetting coil spring 30 which is arranged 50 thereon.

The open wall portion normally closed by the gate or movable wall section 34 constitutes a discharge opening through which certain coin elements may pass sidewise out of the chute 60 when they have been arrested by, and subsequently released from a testing means disposed opposite the wall portion 34.

A finger portion 63 formed as a part of the operating lever 32 extends laterally from a point 65 adjacent the pivoted mounting 31 thereof and extends between the arms of a bifurcated portion 64 formed as a part of the operating lever 24 adjacent its pivotal mounting 25. A spring 68 is associated with the upper ends (Fig. 2) 70 of the operating levers 24 and 32 to urge the same into initial position as shown.

Attached to the body 11 of the coin chute 12, at one side thereof, (Figs. 1 and 6) is a wall member 87 having mounted thereon a member 37 75 and this member 37 co-operates with the wall

87 of the device to form a discharge chute 38 for magnetically attractable or steel slugs, and also for relatively light slugs such as paper, and cardboard slugs and the like, as will be described hereinafter.

Formed in the hinged or movable wall 34 of the upper portion 15 of the runway 12 is an elongated opening 69, the long axis of which is parallel to the runway 15 (Fig. 1), this opening 69 being formed opposite the deflector rib 67 10 formed on the wall 16 so as to co-operate with the latter in ejecting undersized coins, tokens, slugs and the like.

The wall 16 of the uppermost run 15 has formed therein a pair of spaced apertures 72 and 15 73 adapted to allow a free passage for a U-shaped member 74, one leg 75 of which is fixed to the hinged wall 34 as at 76, the opposite leg portion 77 being normally disposed out of the path of coins, tokens, etc., passing along the uppermost runway 15.

The hinged wall 34 is normally urged into closed position as shown in Fig. 3 by a spring 78 which is slidably mounted upon a pin 79 having an enlarged outer end portion 81 and having a loose mounting upon the body 11 as at 82; the pin 79 projects through an opening 83 formed in the hinged wall 34.

Provided in the coin chute 12, at the lower end of upper portion 15 thereof (Fig. 7) is a deflector 39, the purpose of which will be explained hereinafter, and formed in the bottom wall 40 of the coin chute 12, adjacent the deflector 39, is a recess or pocket 41 (Fig. 7) which leads from the coin chute 12 into the discharge chute 38 through a dropout opening 66 formed in the wall 87. The deflector 39 has a top surface 70 which is relatively narrow with respect to the width of the peripheral edge of coins, tokens, slugs, etc., due to a beveling of the two edges 71 for a purpose 40 to be given presently.

The coin chute 12 includes a portion 90 (Fig. 7) which is inclined in a direction which is opposite to the inclination of the upper portion 15 of the same, and pivotally mounted in the coin chute 12 at the entrance to the portion 90 thereof, as at 42, is a gate 43 by means of which relatively light slugs such, for example, as cardboard and paper discs, will be deflected back into the pocket or opening 41, and thence into the 50 discharge chute 38, in a manner which will be described hereinafter.

The coin chute 12 also includes a portion 44 (Fig. 7) which extends substantially parallel to the upper portion 15 of the same and at an angle relative to the portions 90. The coin chute 12 also includes a lower portion 45 which extends in an opposite direction relative to the inclination of the portion 44 of the same and at its lower end this portion 45 of the coin chute is enlarged and bifurcated or divided so as to form two diverging branches or discharge outlets 46 and 47.

Pivotedly mounted as at 48, in the lowermost portion 45 of the coin chute 12, between the branches or discharge outlets 46 and 47 of the same is a deflector 49. This deflector has a relatively sharp-pointed upwardly extending projection or nose portion 50 and this deflector 49 is adjustable about its pivot 48 by means of a screw 70 and slot connection 51—52 with the side wall 53 of the lowermost portion 45 of the coin chute 12.

Likewise pivotally mounted in the lowermost portion 45 of the coin chute 12, as at 54, (Fig. 7) but above the deflector 49 is a second deflector 75

55 and this deflector 55 has a screw and slot connection 56-57 with the side wall 53 of the lowermost portion 45 of the coin chute 12. This deflector 55 has a pointed projection 62, the purpose of which will be explained hereinafter.

10 Mounted upon the body 11 of the device at openings 80 formed between the upper and lower ends of the lowermost portion 45 of the coin chute 12, is a pair of permanent magnets which are generally indicated at 58. These magnets 58 are preferably of the horseshoe type and include a magnet 59 arranged on one side of the lowermost portion 45 of the coin chute 12 and a magnet 60 arranged on the opposite side of the same, in spaced relation with respect to each other to allow passage of a coin through the runway 45, the space between the poles of these magnets 58 setting up eddy currents across the runway for reasons to be given presently.

20 Operation

25 If a magnetically attractive disc or token is inserted into the coin chute 12, through either of the two inlets 13 and 14 thereto (Fig. 7), it will travel by gravity down the uppermost portion 15 of the coin chute 12, along the bottom wall 61 of the same, until it comes opposite to or into alignment with the slot or opening 17, whereupon it will be attracted by the magnet 20 toward the edge part and will be held thereby in the uppermost portion 15 of the coin chute 12 and against traveling farther down the same, and the thus held magnetically attractive or steel disc or slug will be held in this position (as at A, Fig. 7) until the plunger 28 is operated, as will now be described.

30 In order to release the thus held magnetically attractive or steel slug from the uppermost portion 15 of the coin chute 12, and so as to clear the latter for the passage of the intended or proper coin, the operator of the device pushes in on the plunger 28 (right to left, Fig. 2). When the plunger 28 is thus pushed in, its inner end portion or head 21 engages the lower end portion 26 of the lever 32 and thereby pivots the latter, at 35 (clockwise, from full to dotted line position, Fig. 2). When the operating lever 32 is thus pivoted (clockwise, from full to dotted line position, Fig. 3), the lateral extension or pin 33 carried thereby engages the offset arm 35 of the hinged wall 34 and thereby pivots the latter at 38, (clockwise, from full to dotted line position, Fig. 3). Simultaneously with the movement of the operating lever 32 the operating lever 24 will be pivoted at 25 counter-clockwise so as to pivot the magnet carrier 19 clockwise about its mounting 18 through the medium of the pin 23 and the offset arm 22 (the action of the magnet carrier 19 being slightly subsequent to action of the 40 hinged wall 34), thereby moving the magnet 28 away from the uppermost portion 15 of the coin chute 12 and away from the slot or opening 17 which is formed in the latter, thereby releasing the magnetically attractive or steel slug from 45 the position in which it is held, at A, Fig. 7, whereupon the thus released magnetically attractive or steel slug will fall by gravity off the beveled bottom wall 61 into the discharge chute 38, and in this manner a magnetically attractive 50 or steel slug is ejected from the coin chute 12 and is prevented from traveling down the latter into the discharge outlet 47 through which the intended and proper coin or token must be discharged in order to operate the machine or apparatus with which the new device is associated.

55 By actuating the gate 43 and the magnet carrier 19 slowly, there is a possibility that the detained magnetically attractive slug will continue down the runway 15; however, the U-shaped member 74 will have been moved with the hinged 5 wall 34 into a position wherein the leg 77 thereof will be disposed in the path of the advancing steel slug thereby causing the latter to drop down into the pocket 41, whence it is directed through the opening 66 and into the chute 38, thereby assuring that magnetically attractive slugs will be prevented from entering the lowermost runway 45.

10 When the plunger 28 is released the spring 18 will urge the hinged wall 34 into initial position 15 which, in turn, through the arm 35 and pin 33, will urge the lever 32 into initial position, the spring 35 co-operating with the spring 18 and urging the lever 24 into initial position which through the pin 23 and arm 22 urges the magnet 20 carrier 19 into its normal position.

15 If a slug of a diameter slightly smaller than that of the proper standard U. S. coin to which the particular device is adapted, is inserted into either of the slots 13 or 14, that slug, of lesser 25 diameter, will strike the deflector rib 67 and be deflected by the graduated surface 68 thereof plus the momentum of the slug to cause the upper edge of the slug to be tilted out through the opening 69 formed in the wall 34, as shown in Fig. 4, 30 and thereby causing the said slug to flop into the chute 38, it being noted that a slug of proper diameter will be guided along the runway 15 despite the deflector 67 due to the upper edge of said slug or coin bearing against the upper edge 35 of the opening 69 (Fig. 4).

20 If a relatively light slug or disc, such as a paper or cardboard disc or the like, is inserted into the coin chute 12 through either of the inlets 13 and 14 thereto, it will roll by gravity down the bottom wall 61 of the uppermost portion 15 of the coin chute 12 and will roll off from the said bottom wall 61 of the portion 15 of the coin chute 12 onto the deflector 39 by which it will be deflected, along the dotted line path "B", Fig. 7, against the pivoted gate 43, from which it will be deflected or will rebound downwardly into the pocket or opening 41 (Fig. 5) whence it will fall through the drop-out opening 66 into the discharge chute 38, and in this manner a relatively 40 light slug or disc, such as a cardboard or paper slug, will be prevented from passing down the coin chute 12 into the discharge outlet 47 for the intended and proper coin.

25 If a coin or token of the intended and proper size and metallic composition, for example, as a nickel, is inserted into the coin chute 12, through either of the two inlets 13 and 14 thereto, the said coin will travel by gravity down the uppermost portion 15 of the coin chute 12, and will 50 strike the deflector 39 by which it will be deflected, along the path of the full line arrows C Fig. 7, against the gate 43, thereby pivoting the latter at 43, (clockwise, from full to dotted line position, Fig. 7). The intended and proper coin, 55 being heavier than a relatively light disc or slug, such as a cardboard or paper disc, will thus pivot the gate 43 into open position and will pass by the same, whereupon it will continue down the portion 44 of the coin chute 12 and into the lower- 70 portion 45 of the same.

30 As the coin having the intended and proper metallic composition passes down the lowermost portion 45 of the coin chute 12 it will be retarded or slowed up only slightly by the eddy currents set

up in the lowermost portion 45 of the coin chute 12, and hence will drop out of the lowermost portion 45 of the coin chute 12 onto the upright point or projection 50 of the deflector 49, with the center of gravity of the coin slightly to the left of the latter, from which it will travel (along the path D, indicated by full line arrows, Fig. 7) into the discharge outlet 47. It is to be noted at this point that the eddy currents set up in the lowermost portion 45 of the coin chute 12, by the magnet 58, will retard or slow up only slightly a coin which has the intended and proper metallic composition such, for example, as a nickel, as the latter runs down the lowermost portion 45 of the coin chute 12, and hence the intended and proper coin will have sufficient momentum, when it leaves the lowermost portion 45 of the coin chute 12, to move past the point 50 of the deflector 49 and into the discharge outlet 47 of the coin chute 12.

However, if a fraudulent coin or token, which is made of a metal or alloy different from that of the intended coin such, for example, as lead, brass, zinc or copper and aluminum slugs, is inserted into the coin chute 12 it will travel by gravity down the latter, in the manner hereinbefore described relative to the intended coin and will, as it passes through the lowermost portion 45 of the coin chute 12, be slowed up slightly by the eddy currents which are set up therein by the magnet 58 so that when the said fraudulent coin or token emerges from the lowermost portion 45 of the coin chute 12 it will not have sufficient momentum to move past the deflector 49—50 into the discharge outlet 47 for the intended coin and hence will follow the dotted line path E, Fig. 7; and as the said fraudulent coin or token follows this path E it will drop down onto the point 50 of the deflector 49, and will engage the projection 50 of the deflector 49 with its center of gravity at one side of its vertical center and will be deflected thereby into the discharge outlet 46. In this manner a fraudulent coin or token which is composed of a metal or alloy which is different from the metallic composition of the intended and proper coin is prevented from traveling from the coin chute 12 into the discharge outlet 47 of the same and is directed into the discharge outlet 46.

In the event that the metal used in the fraudulent slug is less affected by the eddy currents set up by the magnet 58 than is the metal of the intended and proper coin it will, upon emerging from the lowermost portion 45 of the coin chute 12, have more momentum than the intended and proper coin and hence will strike the point 62 of the deflector 55 by which it will be deflected along the dotted line path F, Fig. 7, into the discharge outlet 46.

It has been discovered that slugs composed of an alloy known as Linotype metal comprising lead, antimony and zinc which, when of proper proportions, has all the qualities necessary to convey that slug to the outlet (47) provided for coins of proper denomination (standard U. S. five-cent piece) with one exception. Linotype metal is softer than nickel and upon dropping a slug of this metal upon a relatively pointed surface, its physical quality is such as to receive an indentation from that relatively pointed surface. To this end the surface 70 of the deflector 39 is narrower in width, with respect to the width of coins, tokens, slugs and particularly with respect to the slug of Linotype metal which, upon dropping onto the surface 70, will be slightly dented

thereby reducing the resiliency of the said slug thus preventing the latter from passing through the gate 43, but causing the same to drop into the pocket 41 whence it passes through the drop-out opening 66 into the chute 38.

It is to be noted, in this connection, that when the metal of the intended coin is such, for example, as silver which is relatively more affected by the eddy currents of the magnet 58 than is the metal of which the fraudulent slugs are composed, then in that event the foregoing arrangement of the outlets 46 and 47, Fig. 7, and which arrangement is specifically designed for a nickel coin chute, must be reversed so that the intended coins will fall into the discharge outlet 46 and the fraudulent slugs will fall into the outlet 47, since in this event the intended coins will be slowed up more by the eddy currents of the magnet 58 than the metal slugs will be, and hence the intended coins will fall into the discharge outlet 46 and the metal slugs will fall into the discharge outlet 47.

It will be noted (Fig. 7) that the deflectors 55 and 49 may be adjusted, by means of their screw and slot connections 56—57 and 51—52, respectively, so as to compensate the deflectors for wear upon the points 62 and 50, respectively, thereof, and to compensate the deflectors for loss of strength by and in the magnet 58 and resulting changes in the strength of the eddy currents set up thereby in the lowermost portion 45 of the coin chute 12.

It is also to be noted, in connection with the present device, that if an attempt is made to operate the same fraudulently by tipping the device out of its normal and proper operating position (counterclockwise, Fig. 7) the fraudulent slug will acquire so much momentum as it travels down the lowermost portion 45 of the coin chute 12 that it will engage the deflector 55 and will be deflected therefrom downwardly into the discharge outlet 46.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. A coin chute including a body member having a chute passage therein with a main entrance and exit opening, and a movable wall portion between said entrance and exit openings and arranged for movement outwardly of said body to provide a sidewise opening in said passage, a magnet carrier supported for movement at a point substantially opposite said movable wall portion and in a direction outwardly of said body, said carrier having a magnet and being normally positioned to support said magnet in close proximity to the fixed wall portion of said body opposite said movable wall portion so as to hold a magnetically attractable element against said fixed wall portion and release said element when said carrier is moved outwardly of said body, means in said chute effective to cause an attracted element to move sidewise out of the chute when said movable wall portion and magnet carrier are moved, mechanism operable to move said carrier and said movable wall portion

outwardly of said body at substantially the same time so as to release an element attracted as aforesaid for movement sidewise out of said passage, together with means for preventing the continued movement through said passage toward said exit opening of a free coin or element, said means being in the form of a U-shaped member attached at one extremity to said movable wall portion and passed through an opening in said fixed wall portion and bent back in a direction upon itself with its opposite extremity spaced from said movable wall portion and movable through an opening in said fixed wall portion to block said passage in the region below said sidewise opening when the movable wall portion is moved as aforesaid.

2. A coin chute comprising a casing having an inclined chute passage with an entrance and exit opening and an open side wall portion between said openings providing a discharge opening, means in said chute for arresting improper coin elements, a closure for said open side wall portion arranged for movement from a normal position to uncover the discharge opening for discharge of said improper coin elements, blocking means including a substantially U-shaped member having one of its terminal extremities attached to said closure with the adjoining arm portion thereof constituting a first blocking arm which is projected through said chute across said passage above the normal path of movement of coin elements down said passage in the region below said exit, said blocking member having a second blocking arm turned back in a direction to reenter said chute for projection across said passage in the region below said first blocking arm but normally disposed out of blocking position relative to said passage when said closure is in normal position, said second blocking arm being moved into blocking position across said passage when said closure is moved out of normal position to open said exit, said first blocking arm being at all times effective to block any coin element which is moving down said passage and any part of which projects above said normal path, both of said blocking arms being effective when the closure is moved out of normal position as aforesaid and discharge means for coin elements which strike said end portion of the blocking member.

3. A coin chute including a descending chute passage, magnetic testing means in the form of a bar magnet having a linear edge portion and supported by a magnet carrier pivotally mounted on said coin chute for movement laterally toward and away from the latter and arranged to normally position the linear edge of said magnet in a linear slot communicating with said passage in said chute and directed in a descending sense along a side of said passage, said chute and passage having a hinged side wall section substantially opposite said slot and movable in a direction outwardly therefrom to provide a sidewise opening in said passage, lever mechanism for simultaneously moving said magnet carrier

and movable side wall section in a direction outwardly of said chute and passage, means yieldingly and normally urging said carrier and movable section toward one another and said passage, and blocking means on said movable wall section and movable into blocking position across said passage closely adjacent the descending end of said sidewise opening when said carrier and movable section are moved outwardly of the passage as aforesaid.

4. A coin chute including a body member providing a descending coin passage having an entrance end and an exit end, said passage having a sidewise exit opening between said entrance and exit ends, a hinged gate member normally closing said exit opening, a magnet carrier pivotally mounted on a wall opposite said exit opening for movement in a direction toward and away from the latter, means for moving said magnet carrier and said gate member outwardly of said chute at substantially the same time, and blocking means in the form of a substantially U-shaped finger attached at one end to said gate and having a free end portion movable into said passage when said gate is in open position said free end portion being disposed when in blocking position adjacent the lower region of said sidewise exit opening and being effective to block movement of coin elements down said passage and to cause movement of such elements sidewise out through said exit opening when said gate member is in open position, the inner wall surface of said passage in the region substantially opposite said sidewise exit opening having means adapted to deflect a coin element sidewise out of said passage.

5. A coin chute comprising a casing having an inclined chute passage with an entrance and an exit opening and an open side wall portion between said openings and providing a discharge opening, magnetic coin arresting means, a pair of pivoted members mounted on either side of said casing opposite said discharge opening and one of the same normally closing the discharge opening and the other normally positioning said magnetic coin arresting means close to said passage to arrest paramagnetic coin elements at a point opposite the discharge opening; means for moving said pivoted members divergently in unison to free an arrested coin and open said discharge opening, and a blocking member attached to a particular one of said pivoted members and extended through said casing with an end portion looped back for blocking movement across said passage near the lower end of said discharge opening when the said particular pivoted member to which it is attached is moved outwardly, said end portion being normally disposed in non-blocking position when the particular pivoted member closes the discharge opening and discharge means for coin elements which strike said end portion of the blocking member.
